CLAIM

The ornamental design for a video display greeting card, as shown and described.

DESCRIPTION

FIG. 1 is a front perspective view of a greeting card of the present invention with front panels in a partially open position;

FIG. 2 is a front perspective view thereof with the front panels in a closed position;

FIG. 3 is a front elevation view thereof with the front panels in the partially open position;

FIG. 4 is a top plan view thereof with the front panels in the partially open position and with a bottom plan view being a mirror image; and,

FIG. 5 is a right side elevation view thereof with the front panels in the partially open position and with a left side elevation view being a mirror image.

A rear elevation view has been omitted as it does not form a portion of the claimed design. The broken lines shown in the drawings are directed to environment, are for informational purposes only, and form no part of the claimed design.
